UNITED STATES PATENT OFFICE.

VIRGIL W. BLANCHARD, OF NEW YORK, N. Y.

FIRE-ESCAPE.

SPECIFICATION forming part of Letters Patent No. 295,723, dated March 25, 1884.

Application filed January 2, 1883. (No model.)

To all whom it may concern:

Be it known that I, VIRGIL W. BLANCHARD, of New York city, in the county of New York and State of New York, have invented certain new and useful Improvements in Fire-Escapes; and I do hereby declare that the following is a full, clear, and exact description thereof, reference being had to the accompanying drawings, and to the letters of reference marked thereon, which form part of this specification, in which—

Figure 1 is a vertical section of a building, showing my improved fire-escape ladder applied to the same and folded up inside of a protecting case. Fig. 2 shows the ladder unfolded. Fig. 3 is an enlarged perspective view of two sections of the ladder. Fig. 4 is a front sectional view of two sections. Fig. 5 is a vertical cross-section of two sections of the ladder. Fig. 6 is a horizontal section through two of the ladder-plates forming part of a ladder-section, showing the clasping-brace and tie-bolt. Fig. 7 is a view of one of the slotted coupling-links.

Similar letters of reference indicate corresponding parts in the several figures.

The letter A designates the wall of a building, at the top of which is a housing, G, having an open bottom and adapted to receive the ladder when it is folded up, and thus protect it from exposure to the weather.

My improved ladder is made up of jointed sections A', of suitable length, connected together by means of links E, so that the sections can be compactly folded and elevated into the housing G. Each section A' is composed of side plates, B, of thin steel, secured rigidly together in pairs by means of angular braces and stays C and tie-bolts a. These braces and stays C are applied to the ends of each pair of side plates, B, and leave spaces between them to receive grooved pulleys D D, around which pass the ropes F, by which the ladder is suspended, folded up, and unfolded.

K K designate the rungs of the ladder, each one of which is composed of a metal rod, k, enclosed by a wooden tube, l, which I find to be superior to metal for grasping and for stepping upon. The ends of the rungs K terminate in angular or beveled tenons g g, which are rigidly secured to the plates B B, and which are adapted to enter angular recesses e,

formed in coupling-links E. All of the rungs K have the beveled tenons g g on their ends, and each ladder-section A' is provided with one rung. The said tenons g are designed to interlock with the recesses c at the lower termini of the slots b in links E. The recesses c in the upper ends of the links E receive beveled tenons g', which are rigidly confined between the lower ends of each pair of plates B B. It will thus be seen that my improved ladder is composed of folding sections and slotted coupling-links, and that when the sections are extended, as shown in Figs. 2, 3, 4, and 5, the tenons g g' will all enter their respective V-shaped recesses c in the links, and thus lock the joints and form a practically rigid ladder from one end to the other, and the rounds will not be deflected from a vertical line beneath the limbs of a person ascending or descending.

The ropes F F are secured to the lowest sections A' of the ladder, and passed over and beneath the pulleys D in such manner that in winding the ropes up the sections will alternately fold to the right and left, so that when folded they will lie snugly together in the manner represented in Fig. 1. The ropes F F are passed over grooved pulleys P, suspended from the upper end of the housing G, and these ropes are connected to a windlass, J, near the roof of the building, which windlass is provided with a hand-crank and a pawl and ratchet-wheel. When the ropes are released and the ladder is allowed to descend, (unfold,) the tenons g g' will adjust themselves in their respective recesses c in coupling-links E, and successively lock the sections rigidly together as they straighten out. During the act of raising or folding up the sections they will successively unlock and lie snugly together, as above described.

Having thus fully described my invention, what I claim as new, and desire to secure by Letters Patent, is—

1. A folding ladder composed of folding sections A' and coupling-links E, constructed as described, in combination with self-locking and unlocking devices, constructed and adapted to operate substantially in the manner and for the purposes described.

2. The combination of folding sections A', locking coupling-links E, ropes F, and pul-

leys D, all constructed and adapted to operate substantially in the manner and for the purposes described.

3. The combination of the folding ladder-sections A', the slotted coupling-links having V-shaped recesses c c, and V-shaped tenons g' at the ends of the sections, all constructed and adapted to operate substantially in the manner and for the purposes described.

4. The combination of folding ladder-sections A', formed of pairs of plates B B, the V-shaped tenons g' g', the clasping-braces C, their tie-bolts, the pulleys D D, and the rungs K, all constructed and adapted to operate sub-

stantially in the manner and for the purposes 15 described.

5. The combination of folding ladder-sections, locking coupling-links therefor, ropes and pulleys P, and a windlass, J, all constructed and adapted to operate substantially 20 in the manner and for the purposes described.

In testimony that I claim the foregoing as my own I affix my signature in presence of two witnesses.

VIRGIL W. BLANCHARD.
